HOUSING FOR RETURN BENDS

Filed Jan. 13, 1932

FIG. 1.

FIG. 3.

FIG. 2.

FIG. 4.

FIG. 5.

INVENTOR

Fred C. Fantz
BY
Harry Lee Dodson.
ATTORNEY

UNITED STATES PATENT OFFICE

FRED C. FANTZ, OF WEBSTER GROVES, MISSOURI

HOUSING FOR RETURN BENDS

Application filed January 13, 1932. Serial No. 586,860.

My invention relates more particularly to that class of return bends which are designed for use in cracking stills for the refining of oil.

Practice has shown that the construction— which formerly prevailed, in which the tubes were rolled into return bends so that when one of them was destroyed during the operation of the still, it was necessary to cut off the other in order to remove the defective tube—has been displaced by a loosely mounted tube such as is shown and described in my Patent No. 1,752,331.

In the stills in which housings of this character are used, the tubes are mounted in nests or banks in which the tubes are placed in very close juxtaposition with the result that there is very little space available for the housing which carries the return bend, connecting adjacent tubes, this fact must be taken into consideration when manufacturing a return bend for this type of still.

My present invention relates more specifically to housings for return bends such, for example, as is described in my copending application, Serial No. 462,749, in which the housing is formed in two sections which are hinged or otherwise secured together; these sections are provided with arcuate flanges adapted to engage shoulders which are on the tubes. My invention is not restricted to use in connection with a housing in which is formed in two halves, but is equally useful when the housing is formed in two or four parts which may be secured together in any convenient manner.

In housings of this character it is necessary to move the arcuate flanges, which interlock with the shoulders on the tubes, from under the shoulders, before the housings and in turn the return bend, can be removed, to permit either the removal of the tubes for the purpose of inspection, replacement or for the insertion of a tube cleaner to remove the ac-

cumulation of coke deposited during the operation of the still.

In some instances where the tubes are very closely spaced there is not sufficient room to move the section housing laterally far enough so that the corners on the inwardly extending arcuate flanges, formed on the housing sections, will clear the shoulders on the tubes.

My invention has for its object to provide a construction which, when utilized in connection with compound housings of the type described, will very materially lessen the distance which it is necessary to move housing sections in order for the arcuate flanges to clear the shoulders on the tubes, thereby enabling the use of the return bend housings on a still in which the tubes have very close centers.

My means of accomplishing the foregoing objects may be more readily understood by having reference to the accompanying drawing, which is hereunto annexed and is a part of this specification, in which—

Fig. 1 is a vertical sectional view through the center of the return bend and tubes one of the housing sections being shown in elevation;

Fig. 2 is a bottom view, the tubes being omitted;

Fig. 3 is a vertical sectional view;

Fig. 4 is a side elevation partly in section of a modified form of my improvement; and

Fig. 5 is a cross section on the line 5—5 in Fig. 4. Similar reference numerals refer to similar parts throughout the entire description.

In the drawing I have illustrated compound housings formed with two and four complementary parts. When in two parts they may be formed in halves and when in four parts there are one pair for each tube. I have illustrated only fragmentary portions of the tubes as obviously they form no part of my invention.

As shown in the drawing the tubes 1 and 2

are provided with shoulders 13 which, as illustrated, are formed integral therewith. It is not essential that they should be a part of the wall of the tube, they can be secured to the tube in other ways if desired.

The faces 3 of the shoulders formed on these tubes are arranged to contact with annular grooves 4, formed in the faces 5, of the return bend 6.

10 The compound housing as shown in Figs. 1, 2 and 3 comprises complementary housing sections 7 and 8 which are provided with upwardly extending portions in which are mounted plates 9 carrying set screws 10, the 15 ends of which contact abutments 11 formed on the return bend 6. The lower portion of the housing sections are provided with inwardly extending arcuate flanges 12 which are adapted to engage the shoulders 13 on the 20 tubes.

If these flanges 12 extend 180 degrees it is necessary to move the housing sections away from the tubes a very considerable distance before the corners of the flanges will clear

25 the shoulders 13 on the tubes. I have found in practice that if I cut away the arcuate flanges 12 for a substantial distance from the plane of the abutting edges of the complementary sections as shown in Fig. 2 at numeral 24, that the amount of movement required to place the arcuate flanges in the position to clear the shoulders of the tubes is materially lessened and a corresponding lessening of the distance between centers of tubes is 30 permitted.

In Figs. 4 and 5 I show the compound housing formed in four sections 14, 15, 16 and 17, one pair for each tube. The sections are each provided with extensions 18 which extend 40 downwardly from the arcuate flanges 12 and are arcuate in cross section and adapted to partially encircle the tubes 1 and 2.

The sections, where this form is employed, are secured together by means of a pair of 45 rings 19 and 20 which are fitted to the outside of the extensions 18 and which are preferably connected by a web 21. If desired a bolt 22 may be employed to hold the rings on the said extensions; or the walls of the ex-

50 tensions 18 and the inner walls of the rings may be tapered so that the rings will stay in place when they are forced onto the tapered surface of the extensions. It will be obvious from the foregoing description, that although 55 I have illustrated a specific type of housing, my invention is not limited thereto but is available for any type of compound housing where there are arcuate flanges which engage shoulders on the still tubes.

60 Having described my invention what I regard as new and desire to secure by Letters Patent, is:

1. In a refinery apparatus, a return bend, a pair of shouldered tubes in communication 65 with said bend, a compound housing for said

bend comprising complementary sections, extensions on the lower part of said housing sections which abut said tubes, arcuate flanges on said housing sections which terminate a substantial distance from the plane of the axes of said tubes, said flanges being adapted to engage the shoulders on said tubes, and detachable means mounted in said sections to draw the faces of the bend and the ends of the tube into a tight joint.

2. In a refinery apparatus, a return bend, a pair of shouldered tubes in communication with said bend, a compound housing for said bend comprising complementary sections, extensions on the lower part of said housing sections which abut said tubes, arcuate flanges on said housing sections which terminate a substantial distance from the plane of the axes of said tubes, said flanges being adapted to engage the shoulders on said tubes, detachable means mounted in said sections to draw the faces of the bend and the ends of the tube into a tight joint and means to hold said sections together.

3. In a refinery apparatus, a return bend, a pair of shouldered tubes in communication with said bend, a compound housing for said bend comprising complementary sections, extensions on the lower part of said housing sections which abut said tubes, arcuate flanges on said housing sections which terminate a substantial distance from the plane of the axes of said tubes, said flanges being adapted to engage the shoulders on said tubes, detachable means mounted in said sections to draw the faces of the bend and the ends of the tube into a tight joint and means mounted on said extensions to hold said sections together.

4. In a refinery apparatus, a return bend, a pair of shouldered tubes in communication with said bend, a compound housing for said bend comprising complementary sections, arcuate flanges on said housing sections which terminate a substantial distance from the plane of the axes of said tubes, said flanges being adapted to engage the shoulders on said tubes, and detachable means mounted in said sections to draw the faces of the bend and the ends of the tube into a tight joint.

5. In a refinery apparatus, a return bend, a pair of shouldered tubes in communication with said bend, a compound housing for said bend comprising complementary sections, arcuate flanges on said housing sections which terminate a substantial distance from the plane of the axes of said tubes, said flanges being adapted to engage the shoulders on said tubes, and detachable means mounted in said sections to draw the faces of the bend and the ends of the tube into a tight joint.

6. In a refinery apparatus, a return bend, a pair of shouldered tubes in communication with said bend, a compound housing for said bend comprising two sections, arcuate flanges on said housing sections which terminate a

substantial distance from the plane of the abutting edges of the housing sections, said flanges being adapted to engage the shoulders on said tubes, and detachable means mounted in said sections to draw the faces 5 of the bend and the ends of the tube into a tight joint.

7. In a refinery apparatus, a compound housing for a return bend which connects a pair of still tubes, said housing comprising a 10 plurality of sections, and inwardly extending arcuate flanges on said sections which terminate a substantial distance from the axes of the still tubes.

FRED C. FANTZ.
